UNITED STATES PATENT OFFICE.

WILLIAM C. MILES, OF CLEVELAND, OHIO.

MUFFLER.

Application filed July 23, 1920. Serial No. 398,499.

To all whom it may concern:

Be it known that I, WILLIAM C. MILES, a citizen of the United States, and a resident of Cleveland, in the county of Cuyahoga and State of Ohio, have invented new and useful Improvements in Mufflers, of which the following is a specification.

The primary object of the invention is to provide a muffler, particularly adapted to be used in connection with internal combustion engines, a means whereby the sounds or reports incident to the release of exhaust gases is reduced in audibility or eliminated without setting up back pressure to such an extent as to materially affect the normal operation of the engine or materially decrease the efficiency thereof.

Other, and more or less dependent, objects of the invention will be apparent in the course of the following description of what I at present regard as the preferred embodiment of the same.

It is a well known fact that exhaust gases released from the cylinders of an internal combustion engine do not travel through the exhaust pipe in a continuous stream or column but on the other hand pass through in a pulsatory manner by reason of the fact that the exhaust gases, in the form of relatively short high tensioned columns or zones, are separated by relatively low tensioned zones or gases. The columns of exhaust gases of relative high tension, separated by relative low tensioned zones, when released from the exhaust pipe directly into the atmosphere by reason of sudden expansion to atmospheric pressure tend to create a partial vacuum at the point of release which partial vacuum is quickly filled in by the surrounding atmosphere, thereby producing sound waves of such intensity as to be audibly transmitted to the adjacent air strata.

The invention consists in effecting the breaking up of a stream of exhaust, which is divided into relatively high and low tensioned zones, into a plurality of similar streams likewise made up of high and low tensioned zones, and further effecting an equalization of the densities or relative vapor tensions of the several portions or zones of the exhaust column so as to reduce the stream or column of exhaust from a condition of alternately high and low tensioned zones to that of a relatively uniformly ten-

sioned stream or column of exhaust which at the final point of release is expanded and dissipated without setting up sound waves or vibrations of a distinctly audible nature.

In the drawings forming a part of this specification wherein like numerals are employed to designate like parts throughout the same,

Figure 1 is a central longitudinal sectional view of the device embodying my invention,

Fig. 2 is a transverse sectional view taken on line 2—2 of Figure 1,

Fig. 3 is a transverse sectional view taken on line 3—3 of Figure 1,

Fig. 4 is a plan view of a corrugated blank,

Fig. 5 is a transverse sectional view taken on line 5—5 of Figure 1, and

Fig. 6 is a transverse sectional view taken on line 6—6 of Figure 1.

Fig. 7 is a modified form of wall plate.

In the drawings, attention being called to Figures 1 to 6 inclusive, wherein is shown a preferred embodiment of my invention, the numeral 10 indicates a cylinder of, preferably, sheet metal which forms the muffler body, within which is arranged a corrugated cylinder 11 formed from a corrugated blank 12 shown in Fig. 4. The blank 12 may be corrugated by any conventional or suitable method and subsequently placed to a punch press equipped with suitable dies and punches to form a plurality of openings 13 and a corresponding number of tongues 14 which serve, in effect, as ejectors within the passages or conduits 15 of the corrugated cylinder 11 to relieve the pressure of exhaust at different localities within the muffler, as will hereinafter be described.

The corrugated blank 12 upon being provided with the tongues 14 is rolled into a cylinder and inserted into the cylinder or main body 10 as shown in Figure 1, whereupon divisional wall plates 16 and 17 are assembled, as shown, respectively at the outlet and intake ends of the muffler to form within the corrugated cylinder 11 a reservoir 17". It will be noted that the wall plates 16 and 17 are substantially identical except, however, the plate 17 is provided with a relatively large opening 18, whereas the plate 16 is solid. The plates as shown are each at their peripheral edges scalloped or cut away to provide openings 19 which register with the conduits or passages 15.

To insure intimate contact between the cylinder or body 10 and the corrugated cylinder 11 alternate arms 20 of the plates 16 and 17 are bent at right angles as shown most clearly in Figures 5 and 6 at 21 to engage the inner surface of the corrugated cylinder at points intermediate alternate corrugations, one angularly bent portion of each of the plates being in contact with the 10 corrugated cylinder at the abutting or adjoining longitudinal edges thereof.

As a means for retaining the plates 16 and 17 in contact with the ends of the corrugated cylinder I have disclosed tie bolts or rods 22 longitudinally disposed within the device and provided with nuts 22' which are run down upon the screw threaded ends of the bolts and into firm engagement with the plates. These tie rods or bolts serve 20 not only as a means for retaining the corrugated cylinder 11 together with the wall plates 16 and 17 against relative movement with respect to each other, but serve also as a means for retaining in position the end 25 plates or heads 23 and 24, thus forming respectively at the outlet and inlet ends of the muffler a final expansion chamber 25 and an initial expansion chamber 26. The end plate 23 is provided preferably centrally 30 with an outlet pipe 27 which may be relatively short as shown or relatively long as the occasion or use to which the muffler is put may require. The end plate or head 24 is constructed particularly for the reception 35 of the exhaust pipe 28 which is held therein by any of the conventional means most generally employed in such connection.

Under certain conditions it may be found 40 desirable to substitute the divisional wall or plate 17' for that indicated by the numeral 17, the plate 17' being substantially the same in construction as that shown in Figure 1, except however it is dished to some extent in order to insure a more streamline entrance of the exhaust into the conduits 15.

In operation the exhaust enters the initial 45 expansion chamber 26 from the exhaust pipe 28, and is there divided, one portion thereof entering the reservoir 17", the remainder passing through the several conduits or passages 15 and into the final expansion chamber 25 from which it passes through the outlet pipe 27 into the atmosphere. The exhaust which enters each 55 of the conduits or passages 15 is in the form of a stream or column of relatively low and high tensioned zones of exhaust, and the same is true also of the exhaust which enters the reservoir 17". When the exhaust enters the reservoir 17" its velocity is decreased due to expansion and a churning action is set up by the obstruction offered by the plate 16. By reason of the churning action the difference of tension in the suc-

cessive zones entering the reservoir is destroyed and a resultant pressure is produced within the reservoir which is greater than the pressure of the low tension zones of exhaust in said conduits. Due to the presence of a pressure in the reservoir 17" greater than the pressure of the low tensioned zones in the conduits 15, it is apparent that as the low tensioned zones pass through the restricted areas of the conduits 75 the exhaust within the reservoir 17" is injected into these low tensioned zones thus tending to transform the pulsatory streams or columns of exhaust of the several conduits into substantially uniformly tensioned 80 ones, thereby eliminating the noise which would otherwise occur at the outlet ends of the conduits.

It may be remarked here that since the exhaust which is trapped within the reservoir 17" is maintained at a pressure somewhat greater than that of the low tensioned zones within the conduits, its potential energy may be utilized when injected into the conduits to thrust the high tension zones of gas forward after they have passed the openings 13 and to facilitate the travel of the high tensioned zones at the entrance ends of the conduits by the ejector action exerted thereupon thus creating a tendency toward increasing the activity of flow of exhaust through the several conduits and relieving excessive pressure at the inlet end of the muffler. Attention is directed to the fact that the normal tendency within the reservoir 17" is that of a reduction in pressure due to the injection of exhaust from the reservoir 17" into the low tensioned zones as they pass the openings 13 and to the ejector action set up by the high tensioned zones of exhaust as they rush through the restricted areas of the conduits 15. Should the rate of flow of exhaust entering the conduits 15 at any time become materially accelerated, an excessive reduction in pressure within the reservoir 100

105 will result due to the increased ejector action set up by the high tensioned zones of exhaust as they rush through the restricted areas of the conduits and this increased reduction in pressure will be transmitted through the opening 18 to the core of the column of exhaust entering the muffler thereby checking the flow of exhaust entering the conduits 15. On the other hand should an excessive pressure then build up within the reservoir 17" the injector action of the exhaust entering the conduits through the openings 13 will be increased to facilitate the travel of the high tensioned zones as they pass the restricted areas of the conduits and to increase the activity of flow of exhaust entering the conduits from the chamber 26 by the ejector action exerted thereupon 110

115 as before mentioned. Due to the 120 125 130

increased activity of flow of the exhaust entering the conduits from the chamber 26 the flow of exhaust entering the reservoir 17" is checked and the pressure therein is 5 reduced.

It is apparent from the above described operation of the device that the tendency at all times and under all conditions is to relieve the pressure within the expansion 10 chamber either by the ejector action set up within the conduits 15 when the exhaust is injected thereinto from the reservoir or by the ejector action, upon the exhaust within the reservoir, which is set up by the rush 15 of the high tensioned zones through the restricted areas of the conduits 15. Not only is there a tendency toward a relief of pressure at the entrance end of the muffler at all times, but under all conditions there is 20 produced a tendency toward building up the pressure of the low tensioned zones to that of the high tensioned zones to transform the pulsatory streams of exhaust of the several conduits into streams of a uniform 25 form or a substantially uniform density.

It is to be understood that various changes may be made in what I have shown and described as the preferred forms of my invention without departing from the spirit of the 30 invention or the scope of the subjoined claims.

Having thus described my invention, what I claim as new and desire to protect by Letters Patent of the United States, is:

35 1. A muffler adapted for connection with an exhaust pipe comprising a plurality of conduits arranged to receive a portion of exhaust from the exhaust pipe and adapted to carry the same in the form of separate 40 columns having relatively high and low tensioned zones, and a reservoir arranged to receive from the exhaust pipe another portion of exhaust independent of that entering the conduits, the reservoir being in communication with said conduits whereby the 45 exhaust of the reservoir is supplied to the low tensioned zones during the passage of the exhaust through said conduits.

50 2. A muffler comprising a plurality of conduits, arranged to receive and adapted to carry separate un-uniformly tensioned streams of exhaust, and a reservoir arranged to receive a quantity of exhaust independent of that received by said conduits, said reservoir being in communication with said conduits whereby the lower tensioned portions of the columns are supplied with exhaust from said reservoir and made to approach the tension of the higher tensioned portions.

55 3. A muffler comprising a casing, a plurality of conduits grouped circumferentially about the axis thereof for carrying separate columns of exhaust, a reservoir for receiving a tension equalizing medium, and means for injecting the tension equalizing medium

into said conduits to create a tendency towards increasing the activity of flow of the columns of exhaust therein.

4. A muffler comprising a final expansion chamber, a plurality of conduits for carrying 70 separate streams of exhaust into said final expansion chamber, a reservoir for storing an expansive medium, and means for injecting the expansive medium from said reservoir into said conduits whereby an ejector 75 action is exerted upon said streams to create a tendency towards increasing the flow thereof through said conduits to said final expansion chamber.

5. A muffler comprising a plurality of 80 conduits for carrying separate columns of exhaust, a reservoir for receiving a tension equalizing medium, said reservoir being in communication with said conduits and means on the one hand for utilizing the 85 tension equalizing medium to create a tendency towards increasing the activity of flow of the columns of exhaust and on the other hand for facilitating the ejection of the tension equalizing medium from said reservoir 90 upon the increase of activity of flow of the exhaust through said conduits.

6. A muffler comprising a casing, an initial expansion chamber, a final expansion chamber, a plurality of conduits arranged 95 intermediate said casing and the axis thereof and connecting said chambers for carrying separate streams of exhaust from the first-named chamber to the final expansion chamber, and a tension equalizing chamber 100 communicating with said conduits, the conduits being adapted to receive the equalizing medium from said equalizing chamber.

7. A muffler adapted to be connected to an exhaust pipe and comprising an initial 105 expansion chamber adapted to receive exhaust from said exhaust pipe, a final expansion chamber, an equalizing chamber adapted to receive a quantity of exhaust from said initial expansion chamber, a plurality 110 of conduits adapted to receive from said initial expansion chamber a quantity of exhaust independent of that received by said equalizing chamber and to carry the exhaust so received to said final expansion chamber, said conduits being provided with openings communicating said conduits with said equalizing chamber and having restrictions in proximity to said openings whereby the exhaust from said reservoir is injected into said conduits to create a tendency toward increasing the activity of flow of the exhaust through said conduits, said restrictions and openings being adapted 120 to facilitate the removal of the exhaust from said equalizing chamber upon the increase of activity of flow of the exhaust through said conduits from said initial expansion chamber to said final expansion 125 chamber.

8. A muffler comprising a casing, a reservoir adapted to receive a tension equalizing medium, a group of conduits intermediate said casing and the axis thereof adapted to project into said conduit to facilitate the travel of exhaust therethrough and to increase the pressure of said low tensioned zones. 65
- 5 carry streams of exhaust, said conduits being provided with openings communicating the conduits with said reservoir, and restrictions formed within said conduits, the restrictions being in proximity to the openings whereby the streams of exhaust in their travel by said restrictions and openings tend to eject the tension equalizing medium from said reservoir. 10
9. A muffler comprising a casing, a corrugated reservoir arranged within said casing, the corrugations of said reservoir forming with said casing a plurality of conduits adapted to carry columns of exhaust, said conduits having restricted areas and provided with openings in proximity to said restricted areas, end plates for said reservoir, one of which is provided with an opening through which enters exhaust to be stored temporarily therein and subsequently injected into said conduits to facilitate the travel of exhaust therethrough. 15
10. A muffler adapted for connection with an exhaust pipe comprising a casing, a reservoir arranged within said casing and forming therewith a conduit having a restricted area and provided with an opening in proximity to the restricted area, said conduit being adapted to receive from said exhaust pipe a quantity of exhaust and carry the same in the form of a stream composed of high and low tensioned zones, whereas said reservoir is arranged to receive from said exhaust pipe an independent quantity of exhaust which is temporarily retained 20 therein under a substantially uniform pressure and subsequently injected into said conduit to facilitate the travel of exhaust therethrough, and to increase the pressure of said low tensioned zones. 25
- 45 11. A muffler adapted for connection to an exhaust pipe and comprising a casing, a reservoir arranged within said casing, a conduit disposed intermediate said casing and the axis thereof, said conduit being provided with a restricted area and having an opening adjacent the restricted area adapted to maintain communication between the conduit and said reservoir, said conduit being adapted to receive from said exhaust pipe a quantity 30 of exhaust and carry the same in the form of a stream composed of low and high tensioned zones whereas said reservoir is arranged to receive from said exhaust pipe an independent quantity of exhaust which is 35 temporarily retained therein under substantially uniform pressure and subsequently in- 40
12. A muffler adapted for connection with an exhaust pipe comprising a casing, a reservoir located within said casing and adapted to receive a supply of exhaust from the exhaust pipe, said reservoir having a conduit exteriorly thereof, which is adapted to carry a stream of exhaust entering the same from the exhaust pipe, said conduit having a restricted area and an opening through which the exhaust is ejected from 70 said reservoir by the ejector action set up by the onrush of exhaust through said restricted area. 75
13. A muffler adapted for connection to an exhaust pipe, comprising a casing having a reservoir arranged therein and adapted to receive a supply of exhaust from the exhaust pipe, a plurality of conduits located intermediate said casing and the axis thereof, each of which is adapted to carry a stream of exhaust entering the same from the exhaust pipe, said conduits being provided with openings through which communication is maintained between said conduits and reservoir, and injector elements 80 within said conduits for utilizing the exhaust traveling through said conduits to facilitate the removal of exhaust from said reservoir. 85
14. A muffler for connection to an exhaust pipe comprising a casing, a metallic lining for said casing, said lining being so corrugated as to form with said casing a plurality of conduits each of which is adapted to receive from the exhaust pipe a stream of 90 exhaust composed of relatively high and low tensioned zones, and means for injecting into said conduits an equalizing medium whereby the lower tensioned zones are made to approach the tension of the higher tensioned zones. 95
15. A muffler adapted for connection to an exhaust pipe comprising a casing, a metallic lining for said casing, said lining being so corrugated as to form with said casing a plurality of conduits each of which is adapted to receive from the exhaust pipe a stream of exhaust composed of relatively 100 high and low tensioned zones, means forming with said lining a reservoir adapted for the reception of a quantity of exhaust from the exhaust pipe, said reservoir being in communication with said conduits whereby the exhaust within said reservoir is injected into said conduits to facilitate the flow of 110 said streams of exhaust therethrough. 115
- 60 WILLIAM C. MILES. 120
